UNITED STATES PATENT OFFICE

159,933

GAME BOARD

Marsden M. Seiferth, Philadelphia, Pa.

Application June 17, 1948, Serial No. 147,030

Term of patent 3½ years

(Cl. D34—5)

To all whom it may concern:

Be it known that I, Marsden M. Seiferth, a citizen of the United States, residing at 5058 Copeley Road, Philadelphia, in the county of Philadelphia and State of Pennsylvania, have invented a new, original, and ornamental Design for a Game Board, of which the following is a specification, reference being had to the accompanying drawing, forming part thereof.

In the drawing—

The figure is a plan view of a game board, showing my new design.

The game board is of conventional thickness.

I claim:

The ornamental design for a game board, as shown and described.

MARDEN M. SEIFERTH.
